S. A. ABRAMSON,
WINDOW FRAME,
APPLICATION FILED JAN. 25, 1921.

1,391,602.

Patented Sept. 20, 1921.

Samuel A. Abramson

INVENTOR

Victor J. Evans

ATTORNEY

WITNESS:

UNITED STATES PATENT OFFICE.

SAMUEL A. ABRAMSON, OF NEWARK, NEW JERSEY.

WINDOW-FRAME.

1,391,602.

Specification of Letters Patent. Patented Sept. 20, 1921.

Application filed January 25, 1921. Serial No. 439,891.

To all whom it may concern:

Be it known that I, SAMUEL A. ABRAMSON, a citizen of the United States, residing at Newark, in the county of Essex and State of New Jersey, have invented new and useful 5 Improvements in Window-Frames, of which the following is a specification.

This invention relates to window pane frames, and comprehends a construction primarily 10 designed for use to support windows in automobile tops or the like, the frame being reinforced at the corners thereof so as to afford the frame proper rigidity to maintain its shape.

15 The nature and advantages of the invention will be better understood when the following detail description is read in connection with the accompanying drawing, the invention residing in the combination, construction, and arrangement of parts as claimed.

In the drawings forming part of this application, like numerals of reference indicate similar parts in the several views and 25 therein:

Figure 1 is a view in elevation looking at one side of the frame.

Fig. 2 is a similar view looking at the opposite side of the frame.

30 Fig. 3 is a sectional view taken on line 3-3 of Fig. 1.

Fig. 4 is a fragmentary view showing the initial arrangement of parts at one corner of the frame.

35 Fig. 5 is a view showing the same corner of the frame after it has been cut away as illustrated.

Fig. 6 is a perspective view of one corner of the frame.

40 Fig. 7 is a detail view of the metallic reinforcing element.

Fig. 8 is a detail view of one of the corner blocks.

As hereinabove stated the frame forming 45 the subject matter of my invention is particularly intended for use in connection with automobile tops, and while it is preferably constructed of wood, it may be constructed of any other suitable material and vary in 50 configuration without departing from the spirit of the invention. As shown in this particular instance, the frame is elongated in plan, and comprises opposed members 10 which are connected by end members 11, the 55 former overlying the ends of the members 11 and secured thereto by means of dowel

pins 12 as illustrated in Fig. 4. The respective members of the frame are designed to provide the ledge 13 against which the pane (not shown) rests. Arranged within 60 each corner of the frame at one side thereof is a corner block 14 which assists in strengthening the frame at this point, each block being provided with a curved face or surface 65 15 as shown.

For reinforcing the frame at the corners with a view of preserving the shape of the frame each corner is cut away to reduce its thickness as illustrated in Fig. 5, during 70 which operation a portion of the dowel pin 12 is also severed, thus providing each side and end member of the frame with a beveled edge or surface 16. Positioned in this cut away portion at each corner is a corner piece 17 whose ends are tapered to correspond to the bevel of the portions 16 against which they fit, the corner piece being of a thickness to provide for uniform dimensions over the entire area of the frame with regard to thickness. Each corner piece has its 80 grain arranged approximately at an angle of forty-five degrees to the grain of the side and end members of the frame, the corner pieces being arranged at the side of the frame opposite the corner blocks 14. The 85 corner pieces 17 are provided with a plurality of openings 18 which register with openings 19 in the side and end members of the frame, and also with openings 20 provided in the metallic reinforcing element 90 21. Each corner of the frame is kerfed as at 22 through the dowel pin 12 and the side and end members respectively, to receive the metallic reinforcing element 21, the latter and said corner pieces 17 being all secured 95 together by means of rivets or other suitable fastening elements 23. By reason of this arrangement of parts, the frame as a unit is strongly constructed at the corners so as to afford the frame maximum strength 100 and rigidity so as to preserve its shape.

While it is believed that from the foregoing description the nature and advantages of the invention will be readily apparent, I desire to have it understood that I do not 105 limit myself to what is herein shown and described, and that such changes may be resorted to when desired as fall within the scope of what is claimed.

What I claim is:

1. A frame of the character described comprising side and end members, dowel pins

- connecting said members at the corners of the frame, corner blocks arranged at one side of the frame, each corner being cut away to provide beveled edges, corner pieces arranged in said cut away portion with their ends contacting said beveled edges, said corner pieces being arranged opposite the corner blocks, and means for holding said corner pieces in position on the frame.
- 10 2. A frame of the character described comprising side and end members, dowel pins connecting said members at the corners of the frame, said corners being cut away to provide opposed beveled edges, corner pieces arranged in said cut away portion with their ends contacting the adjacent beveled edges, each corner and dowel pin being kerfed, a metallic reinforcing element positioned

within said kerf, and fastening elements securing said corner pieces and reinforcing elements associated with the frame.

3. A frame of the character described comprising side and end members, dowel pins connecting said members at the corners thereof, the corners of the frame being cut away to provide beveled edges, corner pieces arranged at one side of the frame with their ends contacting the adjacent beveled edges, corner blocks arranged within the frame, each corner and dowel pin being kerfed, a metallic reinforcing element positioned within each kerf, and fastening elements holding said corner pieces and reinforcing elements associated with the frame.

In testimony whereof I affix my signature. 35
SAMUEL A. ABRAMSON.
